DESIGN FOR A COCKTAIL SHAKER

Helen Hughes Dulany, Chicago, Ill.

Application January 2, 1936, Serial No. 60,386

Term of patent 7 years

To all whom it may concern:

Be it known that I, Helen Hughes Dulany, a citizen of the United States of America and resident of Chicago, county of Cook, and State of Illinois, have invented a new, original, and ornamental Design for a Cocktail Shaker, of which the following is a specification, reference being had to the accompanying drawing, forming a part thereof.

In the drawing in which Fig. 1 is a perspective view of the cocktail shaker shown standing in upright position; Fig. 2 is a perspective view of one of the parts of the cocktail shaker when detached; and Fig. 3 is a perspective view of

the other part of the cocktail shaker with the interconnecting portion carried thereby, the shaker comprises two generally globular enlarged container elements having somewhat flattened end areas, and a cylindrical portion interconnecting the container elements, the cylindrical portions terminating in stepped collars at the point of engagement with the container elements, as shown.

I claim:

The ornamental design for a cocktail shaker substantially as shown and described.

HELEN HUGHES DULANY.
